CLAIM

We claim the ornamental design for a foam packaging assembly, as shown and described.

DESCRIPTION

FIG. 1 is a top-front perspective view of a foam packaging assembly;

FIG. 2 is a front view of the foam packaging assembly of FIG. 1;

FIG. 3 is a rear view of the foam packaging assembly of FIG. 1;

FIG. 4 is a left side view of the foam packaging assembly of FIG. 1;

FIG. 5 is a right side view of the foam packaging assembly of FIG. 1;

FIG. 6 is a top view of the foam packaging assembly of FIG. 1; and,

FIG. 7 is a bottom view of the foam packaging assembly of FIG. 1.

The broken lines in the drawings illustrate portions of the foam packaging assembly that form no part of the claimed design.

1 Claim, 5 Drawing Sheets

Related U.S. Application Data
